UNITED STATES PATENT OFFICE.

EDWARD PAIST, OF PHILADELPHIA, PENNSYLVANIA.

DESIGN FOR A CAKE, &c.

SPECIFICATION forming part of Design No. 24,865, dated November 5, 1895.

Application filed September 20, 1895. Serial No. 563,143. Term of patent 3½ years.

To all whom it may concern:

Be it known that I, EDWARD PAIST, a citizen of the United States, residing at the city of Philadelphia, in the county of Philadelphia and State of Pennsylvania, have invented and produced a certain new and original Design for a Cake, Biscuit, or Similar Article, of which the following is a specification.

The leading feature of my design consists of a cake, biscuit, or the like having a raised body in shape that of a horseshoe, and within the field of the same is displayed a clover-leaf ornamentation.

In the accompanying drawings, Figure 1 is a top or plan view of a cake, biscuit, or the like embodying the features of shape or configuration as well as ornamentation of my design; and Fig. 2 is a sectional view, on the line $x x$ of Fig. 1, of a cake, biscuit, or the like, showing the design of my invention with the clover-leaf ornamentation indented into the body of the article.

Referring to the drawings, A represents the raised body having a horseshoe shape, form, or configuration, and displayed within the field of the same is a clover-leaf ornamentation B, consisting of a series of leaves.

a and a' are two series of ornamentations displayed about and around the body of the horseshoe to represent nail-holes.

b and b' are the end ornamentations of the horseshoe to represent the calks thereof.

Having thus described my invention, what I claim as new, and desire to secure by Letters Patent, is—

The design for a cake or similar article, substantially as shown and described.

In testimony whereof I have hereunto set my signature in the presence of two subscribing witnesses.

EDWARD PAIST.

Witnesses:

J. WALTER DOUGLASS,
THOMAS M. SMITH.
